UNITED STATES PATENT OFFICE.

ELIAS J. EMERY, OF MALDEN, MASSACHUSETTS.

DESIGN FOR A TAP FOR BOOTS, SHOES, OR SIMILAR ARTICLES.

53,732.

Specification for Design.

Patented Aug. 26, 1919.

Application filed May 9, 1919. Serial No. 296,000. Term of patent 14 years.

To all whom it may concern:

Be it known that I, ELIAS J. EMERY, a citizen of the United States of America, residing in Malden, in the county of Middlesex and State of Massachusetts, have invented a new, original and ornamental Design for Taps for Boots and Shoes or Similar Articles, of which the following is a specification, reference being had to the accompanying drawing, forming a part thereof.

In said drawing,

Figure 1 is a perspective view of a tap showing my new design; and

Copies of this patent may be obtained for five cents each, by addressing the "Commissioner of Patents, Washington, D. C."

Fig. 2 is a fragmentary section on the line 2—2 of Fig. 1.

I claim:

The ornamental design for a tap for boots, shoes, or similar articles, as shown.

Signed by me at Boston, in the county of Suffolk and Commonwealth of Massachusetts, this seventh day of May, 1919.

ELIAS J. EMERY.
